UNITED STATES PATENT OFFICE.

ADOLPH MONTAN, OF MONTCLAIR, NEW JERSEY, ASSIGNOR TO EASTERN TOOL & MFG. CO., OF BLOOMFIELD, NEW JERSEY.

CAP FOR FOUNTAIN PENS AND CLIP THEREFOR.

Application filed March 15, 1926. Serial No. 94,653.

This invention relates to an improved cap for fountain pens and the like and an improved form of clip therefor, the advantages of the construction being, first, ease 5 of assembly in the manufacture thereof, second, economy in manufacture; third, security of clip by reason of having two points of contact of the clip against the flap over which the pen or the like is suspended.

10 The invention is illustrated in the accompanying drawing in which Figure 1 is a perspective view of my improved form of clip. Figure 2 is an enlarged section of the cap and the fountain pen with the clip and 15 inside element partially in place, and Figure 3 is a similar view but showing the inside element forced into place to confine the end of the clip and thus hold the clip in position.

20 The clip is made of wire, usually spring wire and while it may be of any shape in cross section, I prefer to make the clip of half-oval wire. This wire is bent into what might be termed a hair-pin shape consisting 25 of the arms 10 and 11. One of the arms as the arm 10 is bent across the end of the other arm as at 12 and then projected as at 13 in an approximate extension of said other arm. For the purpose of identification, the 30 arm 10 I call the outside arm and the arm 11 I call the inside arm. The inside arm is provided with a bulged part 14 at one end thereof, and a bulged part 15 at the other end thereof so that when the clip is in place 35 these bulged parts form the clipping or pinching points, this two point contact holding the pen against canting or tilting and also making the hold more secure. The end 16 of the clip, that is, the closed end

of the hair-pin shaped part acts as a guide 40 when the device is passed over the edge of a pocket or the like. It will be noted that the extension 13 is placed a little out of line with the arm 11 so that when the clip is in place as in Figure 3 the clip is under sufficient spring tension for holding the pen. 45

In the drawing I show a cap which comprises a barrel 17 and I place a hole in the barrel as at 18, the hole being large enough so that extension 13 can be passed through 50 it into the barrel. Then an inside member which may be in the form of a sleeve 19 is forced into the barrel and is usually made of such thin metal that it is distorted sufficiently to pass over the extension 13 of the 55 clip and confine it between the barrel and the sleeve. Another reason for making the sleeve of thin metal is to prevent distortion that might show on the outside of the barrel.

The sleeve is usually made shorter than 60 the barrel so that when it is in place the open end of the barrel can receive the end of the body portion or main part of the fountain pen.

I claim:

A fountain pen cap comprising a barrel with one end open and with a slit in its side, a clip passing through the slit with its exposed end bent to form a spring clasp and with its enclosed end adapted to lie against 70 the inside of the barrel, and an open-ended sleeve of distortable metal softer than the barrel and forced into the barrel whereby the clip and the sleeve are both held in place. 75

In testimony whereof I affix my signature.

ADOLPH MONTAN.
